LOCOMOTIVE STOKER, INCLUDING A
PEEP SIGHT

William Thompson Hanna, Cincinnati, Ohio

Application November 8, 1945, Serial No. 627,308

7 Claims. (Cl. 110—105.5)

1

My invention relates to improvements in stoker apparatus and has to do, more particularly, with locomotive stokers for supplying a solid fuel, such as coal, to a locomotive firebox, through a firing opening in the back wall thereof, and including fuel distributing apparatus associated with said opening and a conduit system for delivering fuel to said distributing apparatus.

The principal object of my invention is to provide a locomotive stoker apparatus so constructed that the fireman, while seated on the fireman's seat of the locomotive cab, may observe conveniently the flow of coal, delivered by the stoker apparatus, over the coal edge to the fuel distributing apparatus associated with the firing opening, so as to make sure that the stoker is functioning properly.

A further object of my invention is to provide means for enabling the fireman to observe the flow of coal over the coal edge, while seated on the fireman's seat of the locomotive cab, which may be closed when not in use and which will prevent a flash-back in the fireman's face, such as might be caused by a sudden increase in pressure within the locomotive firebox, occasioned, for instance, by the bursting of a boiler tube.

Further objects, and objects relating to details of construction and economies of manufacture, will definitely appear from the detailed description to follow. In one instance, I have accomplished the objects of my invention by the devices and means set forth in the following specification. My invention is clearly defined and pointed out in the appended claims. A structure constituting a preferred embodiment of my invention is illustrated in the accompanying drawings, forming a part of this specification, in which

Fig. 1 is a view in side elevation of a locomotive stoker embodying my invention, the back wall of the locomotive firebox being shown in vertical section along the longitudinal centerline of the firebox.

Fig. 2 is a vertical, sectional view through a locomotive stoker embodying my invention, taken in the vertical plane of the longitudinal centerline of the locomotive firebox.

Fig. 3 is a diagrammatic view illustrating the vertical relationship of the sight opening in the side wall of the door housing to the coal edge, and to the line of sight from the eye of a fireman seated on the fireman's seat of the locomotive cab to the point of intersection of the coal edge with the vertical plane containing the longitudinal centerline of the locomotive firebox.

Fig. 4 is a diagrammatic view illustrating the horizontal relationship of the sight opening in the side wall of the door housing to the coal edge, and to the line of sight from the eye of a fireman seated on the fireman's seat to the point of intersection of said coal edge with the vertical plane containing the longitudinal centerline of the firebox.

Fig. 5 is a top plan view of the member containing the sight opening and the closure therefor, the latter being shown in closing position.

Fig. 6 is a top plan view of said member and closure, with the latter shown in open position.

Fig. 7 is a bottom plan view of said member with the closure in the open position.

Fig. 8 is a view of said member and closure in end elevation, and

Fig. 9 is an end elevation of said member and closure, taken looking at the opposite end thereof from that shown in Fig. 8.

In the drawings, the same reference numerals refer to the same parts, throughout the several views.

Referring to the numbered parts of the drawings, I have shown my invention embodied in a locomotive stoker apparatus that is mounted on the back wall 10 of a locomotive firebox, provided with a firing opening 11 therein. A door housing 12 is secured to said back wall, surrounding said firing opening, and said housing is provided with the usual opening in the rear wall thereof, for use in hand firing, which is surrounded by a door plate 13, on which a door of the usual construction (not shown) is mounted. The stoker comprises a conduit section 14, rigidly mounted on the back head 10 by means of a bracket 16, and to which an upper conduit section 15, forming a delivery head, is attached, which opens into the lower portion of the door housing 12. The coal is moved upwardly in the conduit sections 14 and 15 by a rotatable conveyor screw 17. The coal, thus delivered into the lower portion of the door housing 12, flows to fuel distributing apparatus associated with the firing opening 11, by means of which the coal is distributed in the locomotive firebox. This fuel distributing apparatus includes a blast element 19 and a fuel distributing plate 18. Adjustable gates 20 are provided, for regulating the flow of fuel to the firebox, with the upper surfaces of the blast element 19 and the gates forming a fuel edge or surface 21 over which the fuel flows to the distributing plate 18, after being discharged from the screw conveyor.

55 The locomotive stoker apparatus, in which my

Invention is embodied, is substantially that shown in my U. S. patent, No. 2,380,840, issued July 31, 1945, for Stoker apparatus. The blast element 19 may be such as described in my U. S. patent, No. 2,090,628, and the distributor plate 18 may be of the construction shown in my U. S. patent, No. 2,128,940.

In accordance with my invention, I have provided an oblong opening 23, in the side wall of the door housing 12 that is adjacent the fireman's seat of the locomotive cab. A cup-shaped member 24 is integrally secured, as by welding, to the outer surface of said side wall surrounding said opening 23. One wall 25 of the member 24, which may be considered the top thereof, lies in a plane transverse to the line of sight extending from the normal position of the eye of a fireman on the fireman's seat of the locomotive cab to the point of intersection of the coal edge 21 with the vertical plane containing the longitudinal centerline of the locomotive firebox. This top wall 25 has an oblong sight opening 26 therein, and the opening 23 and sight opening 26 are so located that the said line of sight extends from the normal position of the fireman's eye through said opening to the said point of intersection of the coal edge 21 with the vertical plane containing the longitudinal centerline of the firebox. Thus, the fireman may observe the flow of coal over the coal edge, through said opening, without leaving his position on the fireman's seat.

It would be undesirable for this sight opening to remain open at all times, because a sudden increase in pressure within the firebox might result in a flash-back of the fire in the fireman's face, for instance, upon the bursting of a boiler tube. Therefore, I have provided a closure 28 for the sight opening 26, which closure is pivoted at one end, by means of the stud 27, carried by the member 24 and extending at right angles to the plane of the wall 25. A stud 30, having a flanged head 31 spaced from the wall 25, is mounted on said member 24 at the opposite end of the opening 26, and the closure 28 is provided with a notch 29, which receives the stud 30 when the closure is in the closing position. It will be seen that, when the closure is in closing position, a portion thereof is interposed between the body of the member 24 and the flanged head 31 of stud 30, so that said flanged head 31 of stud 30, and the pivot bolt 27, will resist any pressure exerted on the closure 28 through the opening 26 and tending to blow the closure back toward the fireman. Member 24 is provided with a stud 32, which is engaged by the closure 28 in its open position to limit the swinging movement thereof. When the closure is released by the fireman, the weight thereof will carry it back to the normal closed position.

It will be evident that, when the fireman desires to observe the flow of coal over the coal edge, to the fuel distributing apparatus, he may be so easily and conveniently, without leaving his seat, by merely swinging the closure 28 to the open position shown in Fig. 6, and looking through the sight opening 26 and opening 23 in the door housing 12, to the point of intersection of the coal edge with the vertical plane containing the longitudinal centerline of the locomotive firebox. When he has finished observing the flow of coal, he releases the closure 28 and it is returned automatically to the closed position.

Figs. 3 and 4 show, in diagrammatic form, the line of sight of a fireman's eye 33 looking along the line 34 through the center of the sight open-

ing 26. Fig. 3 shows the relation of the eye 33 to sight opening 26 as viewed looking from the firebox towards the rear of the locomotive. Fig. 4 shows the relation of the eye 33 to the sight opening 26 as viewed looking down towards the floor of the locomotive. It will be seen from these two views that the line of sight 34 passes through the central axis of the sight opening to the coal edge.

I am aware that the structure shown herein is susceptible of considerable variation without departing from the spirit of my invention and, therefore, I have claimed my invention broadly, as indicated by the appended claims.

Having thus described my invention, what I claim as new and useful, and desire to secure by Letters Patent, is:

1. In a locomotive stoker for supplying solid fuel to a firebox through a firing opening in the back wall thereof, including fuel distributing apparatus associated with said firing opening, means provided with a fuel edge over which fuel flows to said fuel distributing apparatus, a conduit system for delivering fuel to said fuel edge, and a conveyor screw rotatable in said conduit system, a housing secured to said back wall surrounding said firing opening and into which fuel is delivered by said screw, said housing having a sight opening in the side wall thereof, the axis of said sight opening intersecting the point of intersection of said fuel edge and the vertical plane containing the longitudinal centerline of the firebox.

2. In a locomotive stoker for supplying solid fuel to a firebox through a firing opening in the back wall thereof, including fuel distributing apparatus associated with said firing opening, means provided with a fuel edge over which fuel flows to said fuel distributing apparatus, a conduit system for delivering fuel to said fuel edge, and a conveyor screw rotatable in said conduit system, the combination of a housing secured to said back wall surrounding said firing opening and into which fuel is delivered by said screw, said housing having an opening in the side wall thereof, and a cup-shaped member secured to said side wall of said housing surrounding said opening, said member having a sight opening therein, the axis of said sight opening intersecting the point of intersection of said fuel edge and the vertical plane containing the longitudinal centerline of the firebox.

3. In a locomotive stoker for supplying solid fuel to a firebox through a firing opening in the back wall thereof, including fuel distributing apparatus associated with said firing opening, means provided with a fuel edge over which fuel flows to said fuel distributing apparatus, a conduit system for delivering fuel to said fuel edge, and a conveyor screw rotatable in said conduit system, the combination of a housing secured to said back wall surrounding said firing opening and into which fuel is delivered by said screw, said housing having an opening therein in the side wall thereof, a cup-shaped member secured to said side wall surrounding said opening and having one wall lying in a plane transverse to the axis of said housing opening, said wall of said member having a sight opening therein, the axis of said sight opening intersecting the point of intersection of said fuel edge and the vertical plane containing the longitudinal centerline of the firebox.

4. In a locomotive stoker for supplying solid fuel to a firebox through a firing opening in the back wall thereof, including fuel distributing

apparatus associated with said firing opening, means provided with a fuel edge over which fuel flows to said fuel distributing apparatus, a conduit system for delivering fuel to said fuel edge, and a conveyor screw rotatable in said conduit system, the combination of a housing secured to said back wall surrounding said firing opening and into which fuel is delivered by said screw, said housing having a sight opening in the side wall thereof, a cup-shaped member secured to said side wall of the housing surrounding said opening therein and having a wall lying in a plane transverse to the axis of said sight opening, the axis of said sight opening intersecting the point of intersection of said fuel edge and the vertical plane containing the longitudinal centerline of the firebox, a closure for said sight opening pivotally mounted on said member to swing in a vertical plane about an axis transverse to the plane of said wall and having a notch in the free end thereof, and a shouldered stud secured to said member and adapted to be received in the notch of said closure, whereby, when the closure is in closing position, a portion thereof is interposed between the body of said member and the shoulder of said stud.

5. In a locomotive stoker for supplying solid fuel to a firebox through a firing opening in the back wall thereof, including fuel distributing apparatus associated with said firing opening, means provided with a fuel edge over which fuel flows to said fuel distributing apparatus, a conduit system for delivering fuel to said fuel edge, and a conveyor screw rotatable in said conduit system, the combination of a housing secured to said back wall surrounding said firing opening and into which fuel is delivered by said screw, said housing having an opening in the side wall thereof, a cup-shaped member secured to the side wall of said housing surrounding said opening therein and having one wall thereof lying in a plane transverse to the axis of said housing opening, said wall of said member being provided with a sight opening, the axis of said sight opening intersecting the point of intersection of said fuel edge and the vertical plane containing the longitudinal centerline of the firebox, a closure pivotally mounted on said member to swing in a plane parallel to said plane of said wall, about an axis perpendicular thereto, and a stop carried by said member for limiting the swinging movement of said closure away from closing position.

6. In a locomotive equipped with a firebox stoker which delivers coal from a source at the rear of the locomotive to a transverse distributing edge at the rear of the firebox, said delivery being made approximately along the longitudinal center line of the locomotive, the combination of a peep hole device adapted to be viewed

from one side of the line of delivery of the coal, above it, and to the rear of the firebox, a housing surrounding the delivery end of the stoker, said housing having an aperture in the side wall thereof, the axis of said aperture intersecting the point of intersection of said distributing edge and the vertical plane containing the longitudinal centerline of the firebox; a cup shaped member fastened to the housing, so as to surround the aperture and extending outwardly from said housing toward the viewing side, said cup shaped member having an aperture whose center is on the viewing line; and a cover for the sight aperture in the cup shaped member, said cover being pivoted to the cup shaped member at one side and engageable with a stud in the other side so that the cover may be swung upwardly by the observer to an open position, but will fall back by gravity, when released, to closed position where it is held by the stud and by the pivot against any outward pressure originating in the firebox which would tend to blow it toward the viewing side.

7. In a locomotive stoker for supplying solid fuel to a firebox having a back wall provided with a firing opening, a fuel distributing means disposed within the firing opening, a blast element disposed crosswise of the firing opening in a plane above and to the rear of the distributing means to provide a spillway over which the fuel is fed to the distributing means, a conduit arranged to direct the fuel to the blast element, a rotatable screw conveyor in said conduit to deliver the fuel therethrough and to cause same to flow over the blast element to the distributing means, and a door housing secured to the back wall of the firebox and laterally surrounding the firing opening and blast element, said housing having a sight opening with its axis intersecting the point of intersection of the spillway and the vertical plane containing the centerline of the firebox.

WILLIAM THOMPSON HANNA.
